United States Patent Office

Des. 175,333

Patented Aug. 16, 1955

175,333

TOY AUTO

Laurie J. Campbell, Erie, Pa., assignor to Louis Marx & Company, Inc., New York, N. Y., a corporation of New York

Application February 4, 1955, Serial No. 34,365

Term of patent 14 years

(Cl. D34—15)

Fig. 1 is a side elevation of a toy auto showing my new design;

Fig. 2 is a plan view of the same;

Fig. 3 is a front elevation of the same; and

Fig. 4 is a rear elevation of the same.

Portions of the drawing figures are diagonally lined to indicate transparency.

I claim:

The ornamental design for a toy auto, substantially as shown and described.
